UNITED STATES PATENT OFFICE.

WILLIAM JOHN HARVEY, OF NEW YORK, N. Y.

FOOT AND ANKLE PROTECTING MEANS.

Application filed January 14, 1927. Serial No. 161,046.

This invention relates, generally, to an improved form and construction of foot and ankle protecting means more especially adapted for women's and children's wear; 5 and the invention has reference, more particularly, to a novel construction of light-weight water-proof covering to serve primarily as a protection to the ankles of the wearer, and which may also be made to combine in a novel manner with a foot covering 10 of sandal-like form.

The invention has for its principal object to provide a simple and novel construction of water-proof ankle protectors in the form of gaiters made of comparatively thin rubber adapted to encase the ankles and upper portions of the feet of the wearer to protect such parts from the wet in stormy weather; and the invention has for a further object to provide in combination with the novel ankle protectors a novel construction of sandal-like members adapted to be separably connected with said ankle protectors.

25 Other objects of this invention, not at this time more particularly enumerated, will be clearly understood from the following detailed description of the same.

With the objects of this invention in view, the same consists in the novel construction of foot and ankle protecting means herein-after more fully set forth; and the invention consists, furthermore, in the novel arrangements and combinations of the several devices and parts, all of which will be more fully described in the following specification, and then finally embodied in the claims appended thereto.

The invention is clearly illustrated in the accompanying drawings, in which:—

Figure 1 is a perspective view of the novel construction of water-proof ankle protector having in separable operative connection therewith a novel sandal-like member, all arranged according to and embodying the principles of my present invention:

50 Figure 3 is a perspective view showing one side, and Figure 4 is a similar perspective view showing the opposite side of my novel ankle protector;

Similar characters of reference are employed in all of the hereinabove described views, to indicate corresponding parts.

Referring now to said drawings, the reference character 10 indicates the main body of the ankle protector, the same being made of comparatively thin rubber, and shaped to conform to the general contours of the upper foot and ankle portions of the wearer, so as to comprise an instep covering portion 11 at the front thereof, a heel covering portion 12 at the back thereof, and an ankle embracing portion 13 at the upper end thereof. The said main body thus formed is reenforced at its lower marginal portions by a marginal band 14 of greater thickness than that of the main body, and, in like manner, is reenforced at its upper marginal portions by a marginal band 15, also of greater thickness. The upper portion of the main body 10 is provided with a series of longitudinal grooves 16, 17, 18, 19, 20, 21, 22, 23, 24, 25, 26, 27, 28, 29, 30, 31, 32, 33, 34, 35, 36, 37, 38, 39, 40, 41, 42, 43, ness than that of the main body. Extending upwardly at the back of the main body from the heel portion 12 to the top of said ankle embracing portion 13 is a reenforcing and stiffening rib 16 integrally formed with said main body 10, as shown more especially in Figure 6 of the drawings. Since the main body 10 is preferably made of comparatively thin rubber, the said reenforcing and stiffening rib 16 serves to retain the ankle embracing portion 13 more especially against downward sagging or wrinkling, and thus assures a neat and smoothly fitting appearance of the article when worn. The main body 10 is made discontinuous at its 95 outer side, and is provided along one marginal portion of the opening thus formed with fasteners, preferably in the form of buttons 17. Imbedded in the marginal portion of the opening to which said buttons 17 are applied, is a strip of fabric material 18, such as canvas, to which anchor loops 19 are attached, the exterior eye-portions 20 of which are engaged through the perforate shanks 21 of said buttons 17; the rubber body being molded around the fabric button anchoring strip thus provided, all as shown more especially in Figure 7 of the drawings. The marginal portion of the opposite side of the opening provided in the outer side of said main body is preferably of increased thickness, as shown at 22, to reenforce or strengthen such marginal portion, and formed therein are button-holes 23 for separable engagement with the buttons 17 to close said opening and thus secure the ankle protector in operative enveloping relation to the foot and ankle portions of the wearer's person. Extending across and integral with the forward marginal part of said instep covering portion 11 is a thickened reenforcing band 24, the same being extended at each side downwardly beyond the bottom portion of the main body, said extended portions 25 thus formed being interconnected by a bottom strap 26 integrally formed therewith, and adapted to extend beneath the foot of the wearer so as to retain the ankle protector in position and against upward displacement when worn.

20 Suitably secured to the inner side of the main body 10 at the lower marginal portion 14 thereof, and opposite the lower button 17 at the outer side thereof, is a fastener button 27.

25 The reference character 28 indicate a rubber sandal-member having a sole portion 29, and provided at its rearward end and at each side thereof with rearwardly extending integral fastener straps or tongues 30 having in their extremities button-holes 31.

When the ankle-protector is applied to the foot of the wearer and buttoned on over the shoe so as to extend upwardly thereupon and around the ankle, the same will so cover and enclose the parts as to efficiently protect the stockings from becoming wet or damp, and also from spattering by muddy water, mud or the like, thus affording a very desirable protection from both standpoints of health 35 as well as appearance. It will be understood that the novel ankle-protector may be made in desirable color effects, so that in and of itself it will provide an attractive feature of dress especially for women. The novel sandal member 28 combines with the ankle-protector so as to afford additional protection to the foot, the same being engaged over the shoe, and being thereupon retained against accidental displacement therefrom by 40 buttoning the straps or tongues 30 respectively with the lowermost button 17 at the outer side of the ankle-protector and with the button 27 at the inner side of said ankle-protector, thus providing with the latter a 45 most satisfactory covering protection of very neat and novel appearance.

It will be understood that while I have described in detail one form of my novel foot and ankle-protecting means, I do not thereby 50 limit myself to the precise features of construction illustrated, as I am aware that some modification and variation thereof may be made without departing from the spirit and scope of the invention as set forth in the following claims.

Having thus described my invention, I claim:

1. In combination, an ankle protector made of comparatively thin rubber, comprising a main body open vertically at one side, the meeting margins of said opening having co-operating fastener devices, an additional fastener device at the opposite side of said main body, the forward end of said main body having integral therewith a bottom strap loop to extend beneath the foot of the wearer, and a separable sandal member having rearwardly projecting attachment tongues at each side thereof provided in their extremities with fastener means for separable engagement with fastener devices at opposite sides of said main body.

2. In combination, an ankle protector made of comparatively thin rubber, comprising a main body open vertically at one side, the meeting margins of said opening having co-operating fastener devices, an additional fastener device at the opposite side of said main body, the forward end of said main body having integral therewith a bottom strap loop to extend beneath the foot of the wearer, said main body being further provided with a vertically disposed integral supporting rib extending up the back thereof, and a separable sandal member having rearwardly projecting attachment tongues at each side thereof provided in their extremities with fastener means for separable engagement with fastener devices at opposite sides of said main body.

3. In combination, an ankle protector made of comparatively thin rubber, comprising a main body open vertically at its outer side, the meeting margins of said opening having cooperating closure devices in the form of buttons and button holes, the top and bottom marginal portions of said main body having integrally formed therewith thickened reenforcing bands, the forward end of said main body having integral therewith a bottom strap loop to extend beneath the foot of the wearer, said main body being further provided with a vertically disposed integral supporting rib extending up the back thereof, an additional button fastener connected with the inner side of said main body, and a separable sandal member having rearwardly projecting attachment tongues at each side thereof provided in their extremities with button holes engageable with button fasteners on opposite sides of said main body.

In testimony, that I claim the invention set forth above I have hereunto set my hand this 13th day of January, 1927.
